CHARLES F. ESPICK, OF PLYMOUTH, ASSIGNOR TO HIMSELF AND JOSEPH STOUGH AND JOHN STOUGH, OF MARSHALL COUNTY, INDIANA.

Letters Patent No. 80,933, dated August 11, 1868.

IMPROVEMENT IN TUYERE-IRON.

The Schedule referred to in these Letters Patent and making part of the same.

TO ALL WHOM IT MAY CONCERN:

Be it known that I, CHARLES F. ESPICK, of Plymouth, in the county of Marshall, and in the State of Indiana, have invented certain new and useful Improvements in Tuyere-Iron; and do hereby declare that the following is a full, clear, and exact description thereof, reference being made to the accompanying drawings, and to the letters of reference marked thereon.

In the annexed drawings, forming part of this specification—

Figure 1 represents a side sectional view of the tuyere-iron, and

Figure 2 merely a side view of the same.

A represents the place where the bellows enter the tuyere-iron; B, the upper perforated plate of the same, through which the air is emitted; C is an iron plate, the diameter of which is somewhat larger than that of the perforated plate B in the centre of the iron. This plate C is moved up and down by means of the screw D, which runs through the bottom, E, of the iron. This bottom, E, is connected by a hinge, F, on the side of the iron, and fastened on the other by a latch, G, so that it can be opened down, for letting ashes, dust, and other matter, which may drop down through, escape.

The object of this improvement is to contract the current of air to a small space in the centre of the iron, that the amount of heat and fire may be regulated, as the case may require, by means of the screw D, the fire being increased by turning the screw down, and admitting the heat to the entire surface of the perforated plate B.

I am aware that a tuyere-iron, having a perforated plate with an interior damper for regulating the heat, is not new.

What I claim, is—

The arrangement of the screw D, plate C, and hinged bottom E, with the tuyere-box, constructed and operating as set forth.

In testimony that I claim the foregoing, I have hereunto set my hand, this 31st day of March, 1868.

CHARLES F. ESPICK.
